HOLDER FOR DRAWING INK BOTTLES

Carlos René Cruz Pomar, Habana, Cuba

Application May 3, 1937, Serial No. 140,514

3 Claims. (Cl. 120—57)

This invention relates to holders for drawing ink bottles, and more particularly for India-ink bottles commonly used by draftsmen, and it has for its object the provision of a special holder for holding in raised position the bottle stopper carrying a pen, in order to enable the draftsman to impregnate the ruling-pen with ink from the pen raised on the surface of the drawing-table, or to take ink from the bottle in a separate pen, and thus prevent the stopper from rolling on the drawing-table, as often occurs, thereby splashing or staining with the ink carried by its pen the sheet of drawing fixed on the table, with resulting ruin of the drawing made.

The invention is described with reference to the figures of the accompanying drawing, of which:

Fig. 1 is a perspective view of an India-ink bottle placed on the holder constituting the subject-matter of this invention, the stopper being in closed position.

Fig. 2 is a view similar to that of Fig. 1, showing the bottle in open position with the stopper in raised position to hold the pen in an adequate position for taking ink therefrom with a ruling-pen.

Fig. 3 is a perspective detailed view showing in open angular position the two collars on which the stopper for the ink bottle is mounted.

The holder constituting the subject-matter of this invention comprises a platform or supporting base 1 preferably of sheet metal, to which a sheet-metal member 2 of Z-shape in longitudinal section is fixed by rivets 3 and which has at the end edge of its horizontally extended upper branch a semi-circular notch 4 adapted to receive and serve as a stop for the neck of a bottle 5 of the type commonly known as India-ink bottles for draftsmen's use, and on the central branch 20 of said member 2 is fixed by rivets 6 one of the ends of a metal strip 7 which is bent upon itself to form an upwardly inclined arm 7' in a direction opposed to the upper branch of the member 2 and on whose free end is pivotally connected 25 by a horizontal pin 8 a link 9 which is pivotally connected by means of another horizontal pin 10 with a metal strip 11 bent upon itself to form at its end a collar 12 adapted to embrace the conical upper end 13 of the stopper 14 of the bottle 5 and rest above the annular rim 15 of stopper 14.

To the metal strip 11 is pivotally connected by means of a horizontal pin 16 another metal strip 18 bent upon itself to form at its end a second collar 19 adapted to embrace the stopper 14 beneath the annular rim 15 thereof, the free end of

the strip 18 having a hole 20 and the middle portion of the strip 11 a hole 21, said holes being in transverse alignment in the holding position of the stopper 14 by the collars 12 and 19 to receive a wing-screw 22 and thus fix the two collars in parallel position. In this held position of the stopper 14, the link 9 may be caused to swing upward together with the metal strips 11 and 18 on the horizontal pivot 8 carrying along the stopper 14 with pen 23 impregnated with ink for taking the latter to a ruling-pen, the stopper 14 being capable of freely rotating within the two collars 12 and 19. The stopper 14 will be maintained in raised position by the friction between the juxtaposed portions of pivotally connected 15 arm 7', link 9 and strip 11.

When it is desired to remove the stopper 14 from the holder for substitution of the bottle 5 or for any other purpose, the screw 22 is unscrewed to allow the collar 12 to freely move with relation 20 to the other collar 19, and once the stopper 14 is in raised position, the collar 12 is first removed from above the stopper and then the collar 19 from beneath the pen 23, whereupon the bottle 5 and its stopper 14 will be freed and can be removed from the holder.

It is obvious that the parts and shape of the holder may be slightly changed, without by this reason it may be considered as altered the essential character of the invention, which is such as 30 claimed hereinafter.

What I claim is:

1. A holder for drawing ink bottles, comprising a supporting base for the bottle, a member fixed to the base and having a projection provided with 35 an end notch to engage the neck of the bottle and serve as a stop therefor, a supporting arm fixed to said member and projecting therefrom in a direction opposed to the projection, oscillatory means pivotally mounted on the supporting arm, 40 a pair of relatively movable collars for removably supporting the stopper of the bottle, one of the collars being pivotally connected to the oscillatory means and the two collars being pivotally connected to each other, and means to firmly secure 45 both collars to each other in a parallel position.

2. A holder for drawing ink bottles, comprising a supporting base for the bottle, a sheet member of Z-shape in longitudinal section which is fixed to the base by its lower branch and whose upper 50 branch has a notch at its end edge to receive and retain the neck of the bottle, a supporting arm projecting from the central branch of said member of Z-shape in a direction opposed to the upper branch, and oscillatory means pivotally mounted 55

on the free end of the supporting arm and provided at their free end with a pair of relatively movable collars for removably supporting the stopper of the bottle.

- 5   3. A holder for drawing ink bottles, comprising a supporting base for the bottle, a sheet member of Z-shape in longitudinal section which is fixed to the base by its lower branch and whose upper branch has a notch at its end edge to receive and retain the neck of the bottle, a supporting arm in the form of a sheet bent upon itself and fixed at one end of the central branch of the Z-shaped member, a pair of sheet strips each of

which is bent upon itself to form an end collar and both being pivotally connected to each other by a horizontal pivot, a link pivotally connected at its end respectively to the supporting arm and to one of the collar-forming strips by horizontal pivots, and a locking screw for holding the two collar-forming strips in a parallel position in which both collars embrace the stopper of the bottle above and beneath an annular rim of the stopper.
